SLIDER BOX ASSEMBLY FOR WARP KNITTING MACHINES

Harold C. Noe, Upper Montclair, N. J., assignor to Kidde Manufacturing Co., Inc., Bloomfield, N. J., a corporation of Delaware

Application August 17, 1955, Serial No. 529,054

12 Claims. (Cl. 66—86)

The present invention relates to warp knitting machines and the like, and, more particularly, to an improved slider box assembly including the pusher bars which are operated by the pattern mechanism to impart endwise movement to the guide bars of such machines.

The pattern mechanism of Raschel warp knitting machines, for example, comprising a drum, chain links passing over the drum, and a slide box including pusher bars having a roller at one end for engaging the chain links and having a pusher pad at the other end for engaging the pusher rod at one end of the guide bars. The chain links have cam surfaces for effecting endwise movement of the pusher bars and guide bars in one direction and a strong return spring capable of exerting a force of between about 50 and 100 pounds is connected to the guide bars to pull the guide bars in the opposite direction and thereby urge the pusher bars in that direction to cause the pusher bar rollers to follow the cam surface of the pattern chain links.

In order to effect the desired endwise movement of the guide bars during the knitting cycle, the cam surfaces of the chain links vary in height to place the guide bars in several positions. Presently, particularly in connection with so called high speed Raschel machines, it is contemplated to provide certain links with a surface of increasing height to move the guide bars in one direction to a desired position, a surface of fixed height for maintaining the guide bars in such position, and an abrupt end face which permits the pusher bar roller to drop off onto a succeeding link surface of lesser height whereby the return spring moves the guide bars rapidly in the opposite direction.

In the operation of such a pattern mechanism, the strong return spring imparts considerable kinetic energy to the bar assembly as the roller drops off thereby causing it to strike a surface of lesser height with great impact. Such impact is greater and more severe when the guide bars return from one extreme position to the other extreme position, and, in some cases, causes the bars to rebound and be off gauge as the thread guides pass between adjacent needles which results in breakage of these elements. Such impact also loosens up the guide bar blocks, breaks castings and otherwise impairs the bar assembly whereby shut-downs for repair are frequently necessary.

Accordingly, an object of the present invention is to provide a slider box assembly or the like for warp knitting machines which eliminates the foregoing difficulties and disadvantages.

Another object is to provide such an assembly which damps impact without reducing the speed of the machine and permits safe operation of the machine at even higher speeds than heretofore attained.

Another object is to provide such an assembly having means for accurately and reliably adjusting and maintaining a desired damping effect.

Another object is to provide such an assembly which can be easily installed on either newly constructed or

existing machines equipped with either pattern chain links or a pattern wheel.

A further object is to provide such an assembly which is simple and economical in construction and does not require frequent service or maintenance.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description, and is shown in the accompanying drawing, forming a part 15 of the specification, wherein the single figure is a fragmentary elevational view, partly in section, of a portion of a warp knitting machine embodying the present invention.

Referring to the drawings in detail, there is shown 20 a portion of a warp knitting machine which essentially includes an upright end frame 10, a guide bar rock shaft 11, guide bar hangers 12 (only one partially shown) on the rock shaft, a guide bar assembly 14, a slider box assembly 15 supporting pusher bars 16 (only one shown) for moving the guide bar assembly endwise to the left, as viewed, and a return spring 17 for moving the guide bar to the right as viewed.

The guide bar assembly 14 comprises a guide bar 19, 25 yarn guide elements 20 supported by the guide bar, a post 21 at the pusher bar end of the guide bar for connecting the spring 17, and a horizontally disposed pusher rod 22 mounted on the post.

The slider box assembly or slide comprises a casing 30 which is constructed of upper and lower sections 24 and 25 suitably apertured to provide bearing means for slidably mounting the pusher bar 16 with its ends disposed outwardly thereof. While only one guide bar and only one pusher bar have been shown herein, it is well known that Raschel knitting machines are operated with two or more guide bars and that the slider box assembly accommodates pusher bars corresponding to the maximum number of guide bars capable of being used in the machines.

The end of the pusher bar 16 at the right, as viewed, 35 carries a bracket 26 for supporting a roller 27 which is engaged by and follows the pattern links or pattern wheel (not shown). The other end of the pusher bar carries a bracket 29 having a pusher pad 30 in engagement with the pusher rod 22 and having a depending leg section 31, the purpose of which is about to be described.

In accordance with the invention, the return movement 40 of the pusher bar is damped by shock absorber means which may be of the hydraulic fluid dashpot type. Such an arrangement is conveniently provided by securing a casing section 32 to the underside of the casing section 50 25 which essentially comprises a recess 34 in the upper surface thereof cooperating with the casing section to establish a reservoir for hydraulic fluid, a bore or cylinder 35 extending endwise in the direction of movement of the pusher bar and having an open end facing the guide bar section of the machine for the reception of a plunger 36 carried by the leg 31 of the bracket 29, and valving 55 for controlling the flow of fluid between the reservoir and the cylinder.

Such valving may comprise an inlet port 37 and an outlet port 39 extending laterally between the cylinder and the reservoir, a check valve ball member 40 seated by a spring 41 across the inlet port 37, and a bleed valve needle member 42 for the outlet port 39. The spring is supported in a recess formed in a screw 44 which is threaded into an aperture extending from the underside of the casing to the cylinder.

In order to provide the desired damping effect, which

3

is dictated by the return spring load and the length of the return movement of the pusher bar in the knitting cycle, without adversely affecting the timing of the knitting elements, the needle valve is accurately adjustable. This is accomplished by supporting the needle on a screw 45 threaded into an aperture likewise extending from the underside of the casing section to the cylinder near its closed end.

In operation, when a rise in the cam surface of the pattern control device moves the pusher bar towards the left, as viewed, the plunger moves with the pusher bar and in being retracted from the cylinder creates a suction effect, whereby fluid in the reservoir unseats the ball 40 and enters the cylinder 35 through the inlet port 37. When the pusher bar in following the cam surface "drops off" and is permitted to move rapidly towards the right as viewed, the plunger in being moved into the cylinder creates a compression effect, whereby the ball is seated across the inlet port and fluid bleeds from the cylinder to the reservoir by way of the outlet port 39. The return flow of the fluid is retarded by the needle 42 just sufficiently to dissipate the impact which would otherwise occur when the roller again contacts the cam surface.

From the foregoing description it will be seen that the present invention provides a simple and practical manner of absorbing impact on the pattern cam surfaces to permit high speed operation of the machine without damage to parts thereof and without impairing the timing of the knitting elements.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

I claim:

1. A slider box assembly for warp knitting machines comprising a pusher bar having an end adapted to be engaged by pattern cams and having another end for effecting movement of a guide bar, a casing having bearing means for slidably supporting said pusher bar with its ends disposed outwardly thereof, and shock absorber means operatively associated with said pusher bar and said casing for damping the movement of said pusher bar towards the pattern cams.

2. A slider box assembly according to claim 1, wherein in said shock absorber means includes a dashpot cylinder on said casing and a plunger extending into said cylinder and being mounted on the guide bar engaging end of said pusher bar.

3. A slider box assembly according to claim 2, wherein in said casing has a reservoir for hydraulic fluid and valve means provide fluid flow communication between said reservoir and said cylinder.

4. A slider box assembly according to claim 3, wherein said valve means include a check valve for admitting hydraulic fluid into said cylinder from said reservoir and a bleed valve for controlling the flow of hydraulic fluid from said cylinder into said reservoir.

5. A slider box assembly according to claim 4, wherein said bleed valve is constructed and arranged to render the same adjustable.

6. A slider box assembly for warp knitting machines comprising a pusher bar; means on one end of said pusher bar adapted to be engaged by pattern cams; a bracket on the other end of said pusher bar including a pusher pad

for effecting movement of a guide bar; a casing having bearing means for slidably supporting said pusher bar with its ends disposed outwardly thereof, a reservoir for hydraulic fluid beneath said bearing means and a dashpot cylinder beneath said reservoir extending in the direction of movement of said pusher bar; valve means providing fluid flow communication between said reservoir and said cylinder; and a plunger carried by said bracket extending into said cylinder.

10 7. A slider box assembly according to claim 6, wherein in said valve means include a spring urged check valve for admitting hydraulic fluid into said cylinder from said reservoir upon movement of said plunger outwardly with respect to said cylinder having spring supporting member threaded into the underside of said casing adjacent said cylinder.

15 8. A slider box assembly according to claim 6, wherein in said valve means include a bleed valve for controlling the flow of hydraulic fluid from said cylinder having an adjusting member threaded into the underside of said casing adjacent said cylinder.

20 9. In a warp knitting machine, the combination of a slidably supported guide bar, a slidably mounted pusher bar having means at one end adapted to be engaged by pattern cams to impart endwise movement thereto and having means at the other end thereof for engaging one end of said guide bar and effecting endwise movement of said guide bar in response to the movement imparted thereto by the pattern cams, a return spring for urging said guide bar against said pusher bar and said pusher bar towards the pattern cams, and shock absorber means including a plunger carried by said pusher bar for damping the movement of said pusher bar imparted thereto by the action of said spring.

25 10. In a warp knitting machine, the combination of a slidably supported guide bar having a pusher rod at one end thereof, a slidably mounted pusher bar having means at one end adapted to be engaged by pattern cams to impart endwise movement thereto and having a pusher pad at the other end thereof for engaging said pusher rod and effecting endwise movement of said guide bar in response to the movement imparted to said pusher bar by the pattern cams, a return spring connected to said guide bar for urging said pusher rod against said pusher pad and said pusher bar towards the pattern cam, and shock absorber means including a plunger carried by said pusher bar at the pusher pad end thereof for damping the movement of said pusher bar imparted thereto by the action of said spring.

30 11. In a warp knitting machine, the combination of a guide bar, means for slidably supporting said guide bar, a member adapted to be engaged by pattern cams for slidably moving said guide bar in one direction, a return spring for said guide bar and shock absorber means operatively associated with said member for damping the movement of said guide bar when under the influence of said return spring.

35 12. A warp knitting machine according to claim 11, wherein said shock absorber means include a plunger on said member a fixed dashpot cylinder for receiving said plunger, a reservoir for hydraulic fluid and valve means providing fluid flow communication between said reservoir and said cylinder.
